a corporation of New York

Application November 26, 1927, Serial No. 235,855

26 Claims. (Cl. 274—17)

This invention relates to dictation machines, and more particularly to control means therefor.

In dictation machines, particularly the type used to record the dictation, there is provided a stop-and-start control (usually remote from the machine) and another control by the manual operation of which the machine may be conditioned for either recording or reproducing, or to be neutral, and this control, herein referred to as a sound-box control or conditioning control means, may be manually shifted at will by the operator so that he can record or listen to matter already dictated. In the usual dictation machine construction, the sound-box cannot record when the control device is in neutral or reproducing position, and hence, if the operator inadvertently dictates to the machine while the control device is in neutral or reproducing position, no useful record would be made.

Should the operator discover that the machine is not conditioned to record shortly after he has started dictating, the mistake can be easily remedied, but it is extremely embarrassing and annoying to find, after one has dictated for a long time, that the matter so dictated has not been recorded, for, as is well known, after a matter has once been dictated or spoken, it is seldom that a person can again repeat the thoughts with the same force and style.

In order to obviate this disadvantage, means have been proposed heretofore whereby the start-and-stop control may be rendered inoperable when the sound-box control is in neutral or reproducing position, thereby necessitating manual operation of an auxiliary control provided on the machine to start and stop the machine when reproducing.

An object of the present invention is to further obviate this disadvantage and to so facilitate operation of the machine that operation of an auxiliary control during reproduction is unnecessary. Accordingly, means are provided by this invention to prevent operation of the usual start-and-stop mechanism when the sound-box control is in neutral position and to automatically start the machine for reproducing when the sound-box control is moved to reproducing position. To further avoid incorrect use of the machine, the present invention also provides means to move the sound-box control automatically out of reproducing position into neutral position in which, as stated, the stop-and-start control is inoperable when the operator releases the control. Thus it will be seen that the operator cannot inadvertently dictate, either while the control is in re-

producing position because the sound-box does not remain in that position when released, or while the control is in neutral position because he cannot operate the start-and-stop control.

These features are extremely advantageous, for, by their provision, the operator can give more time and thought to dictation and is not required to cautiously or thoughtfully operate the machine; the operations are performed subconsciously by him, or else he is prevented from doing that which he should not do.

A feature of the present invention is the provision of means whereby the sound-box may be conditioned by the operation of a lever, the position of which is fixed relative to the machine, thus further facilitating the operation of the machine, for, in the usual construction, the operator must more closely observe the machine because the control lever is not fixed relative to the machine but is mounted on the sliding carriage.

Another feature is the utilization of parts of the regular construction of the machine to serve dual purposes.

A further feature is the provision of means controlled by the switch lever whereby the start-and-stop device is rendered inoperable when the switch lever is in position to render the motor for the machine inoperative.

Other objects and advantages will hereinafter appear.

In the accompanying drawings—

Figure 1 is a rear view, partly in section, of a dictation machine with the lower casing removed, showing the present invention embodied therein.

Fig. 2 is a side sectional view with the sound-box control shown in neutral position, showing the stop-and-start control means locked against operation.

Fig. 3 is a side diagrammatic view of parts of the present invention, showing these parts in the positions relative to each other which they occupy when the sound-box control is in recording position.

Fig. 4 is like Fig. 3, but with the parts in reproducing position.

Fig. 5 is a top diagrammatic view taken on line 5—5 in Fig. 2, and shows these parts in the positions relative to each other which they occupy when the sound-box control is in recording position.

Fig. 6 is like Fig. 5, the parts, however, being in their stop-and-start control locking positions which they occupy when the sound-box control is in neutral position (as shown in Fig. 2).

Fig. 7 is a top view, similar to Fig. 5, but shows these parts in the start-and-stop control actuating position (as shown in Fig. 4) which they occupy when the sound-box control is in reproducing position.

The dictation machine shown in the accompanying drawings comprises a main frame 12, having standards 13 and 14 supporting upper and lower guide rods 15 and 16 upon which a sound-box carriage 17 is adapted to slide to and fro longitudinally of the frame to carry a sound-box 18 over the surface of a record 19, mounted on a record-support 20 having a shaft 21 rotatably mounted in a housing 22 forming part of the main frame 12.

Longitudinal movement of the carriage 17 and sound-box 18 over the record surface is accomplished by a rotating feed-screw 23 engaged with a feed-nut 24 carried by the carriage 17.

The sound-box 18 is mounted for up-and-down movement, to accommodate records of different diameters or to follow irregularities of the record-surface, on trunnions 25 carried by a supporting sleeve 26 which in turn is pivotally mounted by a rod 27 in a tube 28 which is slidably mounted in a holder or casing 29 secured to the carriage 17 by screws 30. The tube 28 is longitudinally movable in the casing 29 so as to bring a recording stylus 31 or a reproducing stylus 32 into position to engage a record, or to cause both styli to be raised from the record when the sound-box 18 is in an intermediate or neutral position, as shown in Fig. 2, where it is supported by a lug 33 engaging a stud 34 carried by the casing 29. Hence, when the sliding tube 28 is moved longitudinally in the casing 29, either recording stylus 31, reproducing stylus 32, or neither stylus is in engagement with the record surface, depending upon the position of the sliding tube 28 in the casing 29.

For the purpose of moving the sound-box 18 to any of the positions referred to, the slide 28 is connected by a link 35 to the lower end of a control lever 36 whose upper and exposed end 45 is adapted to be moved by hand. As shown in the drawings, the control lever 36 pivots about the axis of the feed-screw 23. This control lever 36 may be shifted from the neutral position shown in full lines in Fig. 2 forwardly to the dictating position, or rearwardly to the reproducing position, as shown by dotted outline. In the neutral position shown, the feed-nut 24 is, as usual, moved downwardly out of engagement with the feed-screw 23 so that the carriage is free for movement longitudinally of the record to any desired position.

Sound, as for instance matter of dictation, is collected and transmitted to the sound-box 18, by means of a speaking tube 37 connected with the casing 29 for the sound-box slide 28 at one end, and having at its other end a handle 38 provided with a mouthpiece 39, as shown in Figure 2.

In using the machine, the operator grasps the handle 38 and holds the mouthpiece 39 adjacent his lips, so that, as he dictates, sound is received by the mouthpiece 39 and passes through the tube 37 to the sound-box 18 where it actuates the recording stylus 31 which, in turn, cuts helical sound grooves on the record surface while the record-support 20 rotates and the carriage and sound-box moves over the record surface.

Conversely, when the sound-box is in reproducing position and the reproducing stylus 32 engages the record while the record-support rotates and the carriage moves, the diaphragm vi-

brates and produces sound which is transmitted through the tube 37 to the mouthpiece 39 which the operator then holds at his ear.

In the construction shown, movement of the carriage 17 and rotation of the record support 20 is effected by means of a driving device comprising a rotating pulley 40 which is loose on the mandrel shaft 21 but which can be operatively connected therewith by a clutch 41 actuated by means hereinafter described. The pulley 40 is driven through a connecting belt 42 by an electric motor 43 supported on the under side of the flat plate portion of the main frame 12. Rotation of the feed-screw 23 for moving the carriage is accomplished by means of any suitable gear train, such as is indicated in dash and dot circles in Fig. 2 and by the number 44 in Fig. 1, and which is interposed between the feed screw 23 and the rotatable mandrel shaft 21.

In order to control the starting and stopping of the dictation machine so that, during pauses in dictation, the machine will not operate and unnecessarily use up space on the record, the usual clutch mechanism is provided to connect the driving pulley 40 with the operating mechanism of the machine, including the mandrel-shaft 21 and feed-screw 23. This clutch control mechanism comprises a grooved collar 45 mounted within the housing 22 and shifted longitudinally of the shaft 21 by a shifting yoke 46 having up-standing arms 47 provided with pins which enter a groove 48 of the collar 45. The yoke 46 is pivotally mounted on a stud 49 carried by the housing 22 and is so arranged that, when operated, it causes the collar 45 to be moved longitudinally to move a related clutch member 50 into or out of engagement with the teeth 51 on the pulley 40 to control mandrel shaft and feed-screw rotation.

In order that the clutch mechanism may be operated from the handle 38, the latter is provided with a manually operable button 52 connected to the relatively moving parts 53 and 54 of a Bowden-wire 55, which passes through the speaking tube 37 rearwardly to the carriage 17, and from the latter downwardly to a boss 56 forming part of the housing 22, where the outside member 54 of the Bowden-wire is anchored. At this point, the inside member 53 of the Bowden-wire has a plunger 57 slidably moving in the boss 56 and having its front end in engagement with a bell-crank 58 pivoted at 59 as shown in Fig. 1, and having an arm 60 adapted to engage an arm 61 on the clutch shifting yoke 46. Thus, when the button 52 is depressed, the inner member 53 is moved relatively to the outer member 54 of the Bowden-wire and this in turn causes the plunger 57 to move the bell crank 58, which rocks the clutch shifting yoke 46, to start the machine as hereinbefore described. Upon the plunger 57 being retracted by the operation of the button 52, a spring 62 disposed between the yoke and the frame, as shown in Fig. 1, returns the yoke to its former position, at the same time releasing the clutch parts 50 and 51 and stopping the rotation of the machine.

In order to accomplish one of the principle objects of the present invention—namely that of making the operation of the machine simpler and more positive, the present invention provides means to lock the start-and-stop control against operation when the sound-box control is in neutral position and to automatically start or stop the machine operating when the sound-box control

is moved to or from reproducing position respectively.

As shown in the accompanying drawings, this means may comprise a bolt 62 transversely movable in the upper section of the housing 22 by operation of the related sound-box control in a manner described below. With the sound-box control in recording position, the bolt 62 is positioned relative to the clutch shifting yoke 46, as shown in Figs. 3 and 5, and hence, locking lugs 63 do not obstruct movement of the clutch shifting yoke 46 to start and stop the machine.

However, when the sound-box control is moved rearwardly into neutral position, the locking lugs 63 of the bolt 62 pass into slots 64 in the yoke to the positions shown in Figs. 2 and 6 and thus lock the clutch shifting mechanism and hence, the machine against operation.

When the yoke 46 is so locked, the manually operable button 52 of the start-and-stop control cannot be depressed and thus serves to effectively warn the operator that the machine is not conditioned to record, should he inadvertently attempt to do so.

As stated above, the present invention also provides means for automatically starting the machine incidental to the movement of the conditioning control means to reproducing position. While this may be accomplished in several ways within the scope of this invention, in the present embodiment it is extremely advantageous to use the bolt 62 to accomplish this result. Accordingly, the bolt 62 is provided with off-set or cam portions 65 which actuate the clutch shifting yoke 46 to start the machine. This is accomplished when the sound-box control is moved rearwardly to reproducing position, and the bolt 62, which it operates in a manner described below, is moved forwardly causing off-set or cam portions 65 of the bolt to slide in the apertures 64, the offset portions 65 camming the clutch shifting yoke forwardly to the position shown in Figs. 4 and 7, thus actuating the related clutch 41 to start the machine.

By this arrangement, the operation of the machine is greatly simplified, for the machine is automatically started without attention from the dictator when the sound-box control is moved to reproducing position, and no other separate control means need be operated, as heretofore, in order to start the machine.

To further minimize the thought and effort usually required to operate the machine, the present invention provides means for automatically returning the sound-box control from reproducing position to neutral position upon release of the sound-box control lever by the operator. This means, according to the present embodiment, comprises a spring 67 held on the carriage by screws 68 which spring forces the control lever 36 forwardly to the neutral position where its movement is stopped by the free end of the spring engaging an abutment or stop 69 on the carriage. Hence, in order to listen to matter recorded, the operator merely moves the sound-box control lever 36 rearwardly into reproducing position against the pressure of the spring 68 and holds it in this position while listening. When he has heard all he desires, the operator removes his finger from the lever 36 and the sound-box control automatically moves to neutral position under the influence of the spring 68. In this position, as stated above, the start-and-stop device is locked against operation and, before the operator can again depress the button 52 to start the machine

for dictating, he must move the control lever to recording position.

As above stated, movement of the bolt 62 is controlled by the control lever 36. The means for doing this, which it should be noted includes means whereby the bolt 62 may be operated by the control lever 36 with the carriage in any position longitudinally on the machine, will now be described. For this and other purposes, the present invention provides a bail 70 comprising the cross-bar 70' and arms 71 and 72 mounted for arcuate movement about the axis of the carriage rod 15. The arm 72 is provided at its lower end with a stud 73 which enters a slot 74 in the bolt 62 so that movement of the bail causes the bolt to be slid forwardly or backwardly, according to whether the bail 70 is rocked clockwise or counter-clockwise, as viewed in Fig. 2. It should be especially noted that with this construction the usual scale-bar may be used for the cross-bar 70', thereby providing a simple and advantageous construction for the purpose set forth.

To connect the bail 70 with the control lever 36 and yet permit longitudinal movement of the carriage 17 relative thereto, the control lever is provided with a notch 75 in which lies the cross-bar 70' of the bail 70. Since the bar 70' extends clear across the machine and slides in the notch 75, the control lever may be arcuately moved, at any time, irrespective of the location of the carriage longitudinally on the machine.

When the control lever 36 is moved forwardly from neutral position to recording position, as viewed in Fig. 3, the bail 70, through the connection 75, will be moved arcuately forward, rotating the arm 72 which, through the connecting stud 73, moves the bolt 62 rearwardly to the position "A", as shown by dotted lines in Fig. 2, at which time the relative positions of the bolt and clutch shifting yoke will be as shown in Figs. 3 and 5.

Conversely, when the control lever 36 is moved rearwardly to the reproducing position, the bail 70 is rotated rearwardly and the bolt 62 is moved forwardly to the position "B" as shown by dotted lines in Fig. 2, at which time the relative position of the bolt and clutch shifting yoke will be as shown in Figs. 4 and 7.

To further facilitate manipulation of the machine for recording, reproducing or to be neutral and operate the related bolt 62, the present invention further provides a secondary control comprising an upwardly extending arm 76, preferably forming part of the arm 72, which can be operated in the same manner as the control lever 36. This lever has a fixed location longitudinally relative to the machine and, consequently, the operator need not consciously observe the machine to locate the travelling control lever 36 in order to operate the machine, but may subconsciously locate and move the secondary control 76, the location of which is constant. An arm 76' may, for convenience, be located at the opposite end of the machine on the lever 71 as shown, thus providing a control of constant location on both ends of the machine and another traveling with the carriage. Or, if desired, either of these arms 76 or 76' may be omitted. Further, if it is desired, the upwardly extending arm of the control lever 36 on the traveling carriage may be dispensed with, whereupon the machine may be operated entirely by the arms 76 and 76', or by either of them.

As shown in the accompanying drawings, the electric motor 43 is supplied with electric cur-

rent by a pair of wires 78, of which a lead wire 79 may be, as shown, connected directly with the motor 43 and the other lead wire 80 connected with a switch 81, and from the switch a lead wire 82 carries the current to the motor to complete the circuit.

This switch is operated from a remote point on the machine and may, of course, be of any suitable type; but, as shown in Fig. 2, comprises contacts 83 and 84 connected to the leads 80 and 82 respectively, and the circuit is closed by movement of a plunger 85 downwardly, until a bridge 86 closes the gap between the contacts 83 and 84.

As usual, in order that the motor will be automatically stopped when the mouthpiece is placed on a supporting lever 87, the latter, which is pivoted on a stud 88, is pivotally connected at 89 with a vertically movable link 90 provided with an arm 91 which engages the switch plunger 85. The lever 90 is also provided with an extension 92, which passes through an aperture in the main frame where it is provided with a spring 93 which tends to force the link 90 downwardly to operate the plunger 85 and connect the switch to start the motor when the mouthpiece is taken from the supporting lever 87, yet allows upward movement of the link 90 and plunger when the mouthpiece is again placed on the lever 87.

To lock the supporting lever 87 against accidental displacement and thus hold the switch in "off" position when the machine is not in regular use, as at night, a plunger 94 is slidably mounted in a stationary bracket 95 and is adapted to be moved into an aperture, indicated by the dotted circle 87' in Fig. 2, in the supporting lever 87 to hold it down.

In order to prevent the operator from dictating while the machine is inoperable, due to the switch lever being locked, the present invention provides means for locking the clutch mechanism. This means comprises an extension 96, part of the link 90 which extends through an aperture in the frame, and the top portion 97 of which is located under a portion of the clutch shifting yoke. When the switch operating link 90 is, for any reason, in the "off" position as shown in Fig. 2, as, for instance, when the supporting lever 87 is locked by the plunger 94, the top portion 97 of the extension obstructs pivotal movement of the clutch shifting yoke 46 and, consequently, the machine cannot be operated.

However, when the switch operating link 90 moves downwardly to the "on" position, the top portion 97 of the extension moves downwardly sufficiently to permit regular pivotal movement of the clutch-shifting yoke 46 to regularly start-and-stop the machine.

Variations and modifications may be made within the scope of this invention, and portions of the improvements may be used without others.

Having thus described the invention, what is claimed as new and for which it is desired to obtain Letters-Patent, is:—

1. In a dictation machine, the combination of a frame; a sound-box carriage movable longitudinally on the frame; a sound-box control on the carriage having recording, neutral and reproducing positions; and movable means extending longitudinally across the frame in sliding engagement with said sound-box control and adapted to operate said sound-box control irrespective of the location of the carriage longitudinally on the frame.

2. In a dictation machine, the combination of a frame; a machine start-and-stop control; a

sound-box carriage longitudinally movable on said frame; a sound-box mounted on said carriage; a sound-box control operatively associated with said sound-box on said carriage; a bail extending longitudinally across the machine and operating with the sound-box control; and means operated by said bail to effect predetermined conditioning of the start-and-stop control to permit or prevent operation thereof.

3. In a dictation machine, the combination of a frame; a machine start-and-stop control; a sound-box carriage; a sound-box mounted on said carriage; a sound-box control on the carriage movable into recording, reproducing and neutral positions; a bail mounted on said frame and adapted to be swung by the sound-box control; and means controlled by the bail to lock the start-and-stop control against operation when the sound-box control is in neutral position.

4. In a dictation machine, the combination of a machine start-and-stop mechanism; a sound-box carriage; a sound-box mounted on said carriage; a sound-box control on the carriage movable into recording, reproducing and neutral positions; a bail mounted on said frame and adapted to be swung by the sound-box control; and means controlled by the bail to automatically operate the start-and-stop mechanism to start the machine when the sound-box control is moved to reproducing position.

5. In a dictation machine, the combination of a machine start-and-stop control; a sound-box carriage; a sound-box mounted on said carriage; a sound box control on the carriage movable into recording, reproducing and neutral positions; a bail mounted on said frame and adapted to be swung by the sound-box control; and means controlled by the bail to permit manual operation of the start-and-stop control only when the sound-box control is in recording position.

6. In a dictation machine, in combination, state controlling means adapted to set the machine for reproducing or to be neutral, a start-and-stop control, means connecting said start-and-stop control with said state controlling means whereby the start-and-stop control will become inoperative when said state controlling means is changed from reproducing to neutral position, and means for automatically changing the state controlling means from reproducing to neutral position.

7. In a dictation machine, the combination of movable state control means adapted to set the machine for reproducing; mechanism for starting the machine; and means actuated by the state control means when the latter is moved to set the machine for reproducing, adapted automatically to coact with the starting mechanism to set the machine in motion.

8. In a dictation machine, the combination of a frame; a carriage mounted on said frame; a sound box mounted on said carriage; a sound-box control mounted on said carriage movable into a neutral position; manually operable means to operate the sound-box control; a machine start-and-stop mechanism comprising a clutch shifting yoke; and means for locking the clutch shifting yoke against operation when the sound-box control is in neutral position.

9. In a dictation machine, the combination of a frame; a carriage mounted on said frame; a sound-box mounted on said carriage; a sound-box control mounted on said carriage movable into reproducing and nonreproducing positions; a machine start-and-stop clutch; and means con-

- trolled by the sound-box control for automatically operating the clutch when the sound-box control is moved to reproducing position.
10. In a dictation machine, the combination of 5 a clutch; a clutch shifting yoke; an electric motor for driving the machine; a switch to control the electric motor having "on" and "off" positions; and means for locking the clutch shifting yoke against operation when the switch is in "off" position.
11. In a dictation machine, in combination a traveling carriage; a sound-box mounted thereon; a movably mounted bar extending in the path of travel of the carriage; movable sound-box control means on the carriage; means interconnecting the bar with the sound-box control means for operation one by the other in any longitudinal position of the carriage; start-and-stop mechanism on the machine; and means 15 operated by the bar for controlling the start-and-stop mechanism.
12. In a dictation machine, the combination of a frame; a machine start-and-stop control; a sound-box carriage longitudinally movable on 20 the frame; a sound-box mounted on said carriage; a sound-box control on the carriage adapted to set said sound-box alternatively to be operative or inoperative; movable means extending longitudinally across the frame and operatively connected to said sound-box control; a manually operable lever mounted on an end of said movable means; and means operated by said movable means for automatically controlling said start-and-stop control.
13. In a dictation machine, the combination of a frame; a sound-box carriage having a range of sliding movement longitudinally on the frame; a sound-box mounted on said carriage; a sound-box control on the carriage movable into recording, reproducing or neutral positions; and a bail 25 pivotally mounted on the frame and extending longitudinally across the machine with a manually operable lever mounted at an end thereof by the operation of which the sound-box control 30 may be operated irrespective of its location longitudinally of the machine.
14. In a dictation machine, the combination of a start-and-stop mechanism; an electric motor for driving the machine; a switch to control the 35 electric motor having "on" and "off" positions; and means operated by the switch for locking the start-and-stop mechanism against operation when the switch is in "off" position.
15. In a dictation machine, in combination, a 40 frame; a machine start-and-stop mechanism mounted on said frame; a carriage mounted on said frame; a sound-box mounted on said carriage; a sound-box control operatively connected to said sound-box and adapted to set said sound-box alternatively in recording, neutral and reproducing positions; manually operated means 45 for moving said start-and-stop mechanism into one position to start the machine; means for automatically moving said mechanism into position to stop the machine; controlling means coacting with the sound-box control adapted to lock the start-and-stop mechanism when the sound-box control is in neutral position and to 50 actuate the start-and-stop mechanism when the sound-box control is in reproducing position, said start-and-stop mechanism being freely operable when said sound-box control is in recording position; and means operable either from the carriage or a point on the frame for actuating both 55 the sound-box control and said start-and-stop mechanism controlling means.
16. In a dictation machine, the combination of a frame; a carriage mounted on said frame; a sound-box mounted on said carriage; a sound-box control mounted on said carriage movable into a neutral position; a machine start-and-stop mechanism comprising a clutch-shifting yoke; means for locking the clutch-shifting yoke against operation when the sound-box control is in neutral position; and means on the frame for manually operating said sound-box control.
17. In a dictation machine, the combination of a frame; a carriage mounted on said frame; a sound-box mounted on said carriage; a sound-box control mounted on said carriage movable into reproducing and non-reproducing positions; a machine start-and-stop clutch; means controlled by the sound-box control for automatically operating the clutch when the sound-box control is moved to reproducing position; and means on the frame for manually operating said sound-box control.
18. A phonographic dictating machine having shift means for alternating the machine from dictating to listening condition and vice versa through an intermediate neutral condition, and control means for starting and stopping the machine operable independently of the said shift means when the machine is in dictating condition, characterized by means for automatically starting the machine when adjusted to listening position and for automatically arresting the operation of the machine upon return adjustment to neutral or dictating position.
19. In a phonographic dictating machine, starting and stopping means, adjusting means for alternating the machine from dictating to listening condition and vice versa, said starting and stopping means being operable independent 105 of the adjusting means when the machine is in dictating condition, and means for automatically starting the machine by the adjustment to listening condition.
20. A phonographic dictating machine includ- 110 ing a reciprocating control for starting and stopping the machine, and an oscillatory shift lever for alternating the machine from dictating to listening condition and vice versa, and a locking member actuated by the shift lever 115 for initially locking the reciprocating control member against independent movement and by further adjustment of said lever actuating the control member to start the machine.
21. A phonographic dictating machine includ- 120 ing a manually operable control member for starting and stopping the machine and a manually operable shift member for alternating the machine from dictating to listening condition and vice-versa, the control member being independently operable while the machine is in dictating condition, and means actuated by the shift member for initially locking the control member against independent operation and upon further adjustment of the shift member to place the machine in listening condition automatically actuating the control member to start the machine.
22. A phonographic dictating machine includ- 130 ing a motor, a shiftable clutch for connecting the motor with the actuated mechanism, starting and stopping means controlling the clutch, and shift means for changing the operating condition from dictating to listening and vice versa, characterized by means for automatically starting the machine upon its adjustment to listening condition.
- 135
- 140
- 145

and for arresting the operation of the machine upon its return from listening condition.

23. A phonographic dictating machine including a movable start and stop member, an oscillatory shift lever for changing the machine from dictating to listening condition and vice versa, and a cam member actuated by the shift lever and having operative engagement with said start and stop member to reciprocate the said member upon oscillation of the shift lever.

24. A phonographic dictating machine including a movable start and stop member, an oscillatory shift lever for changing the machine from dictating to listening condition and vice versa, and a movable cam plate operatively connected with the shift lever for unison movement therewith, said cam plate being positioned to permit freedom of movement of the start and stop member when the machine is in dictating condition, and actuated into locking engagement with the start and stop member, upon adjustment of the machine from dictating condition, and further operative to adjust said member to start position upon adjustment of the machine to listening condition.

25. A phonographic dictating machine, including start and stop means and means for adjusting the machine from dictating condition to listening condition and vice versa, and interlocking means between the start and stop means and the adjusting means operable by the adjustment of the machine from dictating to listening condition and vice versa by which the start and stop means is released for freedom of movement when the machine is in dictating condition and is automatically adjusted to starting position by the adjustment of the machine to listening condition.

26. In a phonographic dictating machine, a rotary record carrier, a driving clutch therefor, manually operable means for actuating the clutch into driving engagement with the record carrier, a movable recorder and reproducer carrier, and means for automatically engaging said clutch with the record carrier upon the movement of the recorder and reproducer carrier into reproducing position.
